UNITED STATES PATENT OFFICE.

THOMAS PHARES, OF EUREKA, CALIFORNIA.

LIFTING-JACK.

SPECIFICATION forming part of Letters Patent No. 314,716, dated March 31, 1885.

Application filed August 19, 1884. (No mod. de.)

To all whom it may concern:

Be it known that I, THOMAS PHARES, of Eureka, Humboldt county, State of California, have invented an Improved Lifting-Jack; and I hereby declare the following to be a full, clear, and exact description thereof.

My invention relates to certain improvements in that class of implements known as "lifting-jacks," and it consists in a novel oscillating head which is provided with two alternately-acting pawls. These are adapted to raise a rack-bar, so as to elevate anything which may be placed upon the top plate. In combination with this mechanism I provide a friction-clamp operated by an eccentric or cam, so as to press against the rack-bar when desired, and a means for releasing the pawls, so that the rack-bar and its load may be lowered at will by the use of the friction-clamp, while the pawls are held out of contact with the bar, as will be more fully described by reference to the accompanying drawings, in which—

Figure 1 is a vertical section of the standard, showing the pawl block or head with its pawls 25 engaging with the rack-bar, and the frictional clamp drawn back out of contact. Fig. 2 shows a similar section with the pawls disengaged and the frictional device in contact with the rack-bar. Fig. 3 is an enlarged perspective 30 view with part of the side broken away. Fig. 4 is a front view showing plate for disengaging the pawls.

A is the standard of my jack, which may be formed of wood or iron, and is provided with 35 a suitable base, as shown. This standard is slotted or formed with a deep channel from one side, and the rack-bar B is adapted to move up and down within the channel, which serves as a guide for it. This rack-bar has a plate, C, 40 at the top, upon which the article to be lifted will rest conveniently, and an anti-friction roller, D, at the lower end moves in contact with the rear of the channel and standard. Another roller, E, is fixed near the top of the standard, 45 and fits into a chamber or depression, F, in the rear part of the rack-bar, so that the latter moves easily, and not much of the lifting power is lost by friction. The pawl block or head G is adapted to receive a lever at its back,

and has a pivot-pin, H, near the center of the 50 side which fronts the rack-bar, and the pawls I and J are pivoted or hinged one above and one below this axis, so that when the block is made to oscillate about its axis the pawls alternately act to push the rack-bar upward, one 55 being drawn back for a new hold while the other is forcing the bar upward, thus giving it a nearly continuous movement to raise the article which rests upon the plate C. When it is desired to lower the plate C with its load, 60 the pawls I and J are disengaged from the rack-bar, and the frictional clamping device is employed to lower the rack-bar steadily. This device consists of the plates or jaws K, which have their front edges adapted to press 65 against the sides of the rack-bar. A block or head, L, is perforated at the rear to receive the lever by which it is actuated, and this block has a tongue, M, which projects between the side plates, K. Trunnions N, which project from each side of the tongue M, pass 70 through holes in the plates K, so that their ends are flush with the outside faces of the plates. A hole, O, is bored eccentrically through the trunnions, and a pin through this 75 and the sides of the standard serves as an axis about which the head and trunnions are turned by the action of the lever. It will be seen that when this head stands in such a position that the pin or axis is nearest to the rack-bar the 80 holding-jaws K will be drawn back from the bar and will not press upon it at all. When the lever is moved so as to turn the eccentric trunnions about the axis, they will act to force 85 the jaws firmly against the sides of the rack-bar, and thus hold it in any position by frictional contact, and this may be regulated by a movement of the lever so as to correspond with the load, and thus lower it steadily after the lifting-pawls have been disengaged. 90

In order to lift the pawls I and J out of contact with the teeth of the rack-bar, so as to permit the latter to be lowered when desired, I employ a sliding plate, P, which is fitted to slide up and down the front of the rack-bar, 95 between it and the rear portion of the pawl-carrying head G, as shown in Figs. 3 and 4. This plate has elongated vertical slots at Q,

through which the pawls project so as to engage with the teeth of the rack-bar, and the pawls are pressed forward by springs R, acting against their backs, as shown in dotted lines at Fig. 3. The lower end of the plate P is turned upward at S, and a block, T, is fixed so that this turned-up end slides over it, and may either be drawn down below its lower end, so that the pawls will pass through slots 10 Q and engage with the rack, or it may be moved upward until the part S engages with a notch, (shown at U, Fig. 3,) when the lower ends of the slots Q will press pawls backward until they are disengaged from the rack-bar, 15 so that it may be lowered at will.

V is a pawl hinged to the upper portion of the head G, so that its point may be raised to engage with a notch, W, in the lower part of the head L when the weight has been raised 20 to a sufficient height, and if it is desired again to lower the rack-bar B this pawl V is raised until its point engages notch W, the head G being pressed downward. When the head G is again lifted by its lever, the pawl V 25 will also push head L upward, thus rotating eccentric trunnions N, and causing plates K to press against the sides of the rack-bar with sufficient friction to hold it and its load. The sliding plate P is then moved upward until it has disengaged the pawls I and J from 30 the rack-bar, which is thus left supported by the frictional pressure of the plates K. By depressing the lever in the head G this pressure will be relieved to such an extent as to 35 allow the rack-bar to slide down at any desired rate of speed, thus lowering the load again.

Having thus described my invention, what I claim as new, and desire to secure by Letters Patent, is—

1. The friction-clamp consisting of the jaws 40 K, the head L, with its operating-lever, and the trunnions N, turning in holes in the plates or jaws K, and having a journal pin or axis eccentric to the circumference, whereby the jaws are forced against the rack-bar by the movement of the lever, substantially as herein described.

2. In a lifting-jack, the standard A, vertically-moving rack-bar B, the pawl-block G, with its lever and pawls I and J, with the plate 50 P, in combination with the friction-clamp K, L, and N, substantially as and for the purpose herein described.

3. In a lifting-jack, the oscillating pawl-block with the pawls I and J engaging the 55 rack-bar, a friction-clamp, K, with its eccentric operating-head L, having a recess or notch at its lower side, together with an arm or pawl, V, hinged to the upper part of the block G, so that it may be made to engage with the recess 60 in the head L, substantially as and for the purpose herein described.

4. In a lifting-jack, the standard with a vertically-sliding rack-bar, an oscillating head having pawls I and J engaging the rack-bar, 65 together with the sliding plate P, having slots through which the pawls project, and by which they may be thrown out of contact with the rack-bar, substantially as herein described.

In witness whereof I have hereunto set my 70 hand.

THOMAS PHARES.
